ENGINE DRIVEN CHAIN SAW AND OILING
SYSTEM THEREFOR

Elmer C. Kickhaefer, Cedarburg, Wis.

Application April 21, 1948, Serial No. 22,333

12 Claims. (Cl. 81—32)

1

This invention relates to oiling systems for chain saws and particularly to high speed portable saws requiring continuous lubrication in service where the power source may be an internal combustion engine as here shown, or some other type of power such as air motors or electric motors.

A principal object of the invention is to provide a lubrication system for directing oil to the chain saw mounted at the engine driven end of the saw and operative with the clutch engagement device so that oil is delivered to the saw automatically as the saw is operated and delivery stopped when the clutch is disengaged so that no oil is wasted while the engine is running and the saw not in use.

Another object of the invention is to provide a system for lubricating the chain of an engine driven chain saw and operable therewith which is disposed adjacent the chain for direction of the oil immediately thereto.

Another object of the invention is to provide a system for lubricating the chain of an engine driven chain saw operable therewith which is disposed adjacent the chain and readily movable therewith relative to the engine to various cutting positions.

Another object is to provide a system for lubricating the chain of an engine driven chain saw having a reservoir of substantial capacity and which is disposed adjacent the chain and movable therewith relative to the engine to various cutting positions without interfering with normal cutting operations.

Another object of the invention is to provide a lubrication system which is positive and efficient in operation and which is readily adjustable from the engine operator's position.

Another object is to provide a lubrication system that is unitary, compact and efficient, and of relatively inexpensive construction.

These and other objects and advantages of the invention will appear more fully in the following description of a preferred embodiment of the invention illustrated in the accompanying drawings.

In the drawings:

Figure 1 shows an engine driven chain saw with blade disposed for vertical cuts and for carrying;

Fig. 2 is a view similar to Fig. 1 showing a part of the saw blade disposed horizontally as for cutting down trees;

Fig. 3 is a view in part in side elevation and in part in cross-section of the transmission grease case and oil reservoir prior to assembly;

2

Fig. 4 is an axial section through the transmission case showing the clutch control mechanism in operative position;

Fig. 5 is a view similar to Fig. 4 showing the mechanism in inoperative position;

Fig. 6 is a side elevation with parts broken away and sectioned showing the transmission case and oil reservoir;

Fig. 7 is a cross-sectional view taken generally on line 7—7 of Fig. 6 and showing the fluid circuit of the oiling system; and

Fig. 8 is a view in side elevation of the transmission grease case showing the driving sprocket, a part of the saw chain and the oil nozzle for directing a stream of oil to the chain.

The chain saw shown in the drawings includes the engine 1, the transmission case 2 and the cutting chain 3 driven by engine 1 through the transmission gears 4 and 5 in case 2.

20 The cutting chain 3 is carried by the flat guide rail 6. Grooves 7 in which lugs 8 of chain 3 ride are provided in the upper and lower edges of rail 6 to guide the chain.

The driving chain sprocket 9 and an idler sprocket, not shown, carried within the tail stock 10 are located adjacent opposite ends of rail 6 and in alignment with grooves 7 to carry the chain around the opposite ends of the rail.

Horns 11 are carried by case 2 and tail stock 10 at the upper and lower working ends of rail 6 as a stop or to engage the wood, not shown, being cut. One end of rail 6 is bolted to tail stock 10 and the opposite end is bolted to the transmission case 2 which carries driving sprocket 9 on the hollow transmission shaft 12 extending axially through case 2.

30 The engine crankshaft 13 extends into transmission case 2 at right angles to shaft 12 and carries the beveled pinion 4 which meshes with gear 5 secured on shaft 12. The clutch 14 mounted on shaft 12 with sprocket 9 outside of case 2 provides for the selective connection between the engine 1 and saw chain 2 for cutting.

35 The ring lock 15 joins engine 1 and case 2 and provides for rotational movement of case 2 and the saw chain 3 therewith relative to engine 1 about the axis of crankshaft 13 so that the saw may be disposed horizontally and vertically in either direction for various cutting operations while maintaining the engine upright.

40 Transmission case 2 is substantially cylindrical having a closed end through which shaft 12 extends and an opposite open end closed by the oil reservoir, as will be described. Transmission case 2 is normally filled with grease, not 45 shown, for lubrication of gears 4 and 5.

3

The reservoir for the oil, which is not shown, for lubrication of saw 3 comprises two shells 16 and 17 and the gasket 18 disposed between the rim of each shell to provide a seal therebetween. Shell 16 is disposed within the open end of case 2 and is provided with a circumferential shoulder 19 to fit the circumferential edge of case 2. The gasket 20 is provided between case 2 and shell 16 to seal the closure. The bolts 21 shown extending through shells 16 and 17 into case 2 serve to secure the assembly tightly together.

Shell 17 is shaped to provide two chambers 22 communicating with shell 16 and spaced to accommodate on the outside and therebetween the clutch operating mechanism, as will be described.

Shaft 12 extends from shell 17 through shell 16 and case 2 and is journaled in bearings 23 carried by case 2 and shell 17. Oil seals 24 in case 2 and shells 16 and 17 are provided on shaft 12 to retain the grease in case 2 and the lubricating oil in shells 16 and 17.

The rod 25 for operating clutch 14 is disposed within shaft 12 and is connected at one end to one element of the clutch. The opposite end of the rod projects between chambers 22 of shell 17 and carries the clutch thrust plate 26.

The clutch spring 27 disposed on rod 25 within shaft 12 normally biases and secures clutch 14 in engaged position. The clutch throwout arm 28 carrying the adjustable pin 29 to engage thrust plate 26 is pivotally secured at its lower end by link 30 to shell 17 between chambers 22. The clutch toggle lever 31 on the upper end of arm 28 is connected to shell 17 by link 32 to move arm 28 and effect disengagement of clutch 14 through pin 29 engaging thrust plate 26 on rod 25.

Control of clutch 14 is provided through the flexible cable 33 connecting lever 31 and the finger control 34. Control 34 may be mounted on either one of two handles 35 secured to the engine 1. Handles 35 are provided for carrying the engine end of the saw and manipulating the same by the engine operator. The handle 36 extending from tail stock 10 of the saw is provided for carrying that outer end of the saw and manipulating the same by a second operator. The handle 36 may be eliminated or removed where the saw is operated by one man.

The pump 37 for pumping the oil from the reservoir to the saw comprises the plunger 38 carried within the body of shell 16 beneath shaft 12 and the connecting ring 39 eccentrically mounted on shaft 12 to reciprocate plunger 38 upon rotation of the shaft.

The passage 40 in shell 16 provides for supply of the oil within the reservoir shells 16 and 17 through the oil strainer 41 to the pump 37. A one way check valve 42 connects the pump 37 with the recess 43 between shells 16 and 17. The ring gasket 44 in recess 43 is adapted to withstand the high pressures developed therein by the pump.

The passage 45 in shell 16 communicates with recess 43 and the lower end of conduit 46 disposed within one chamber 22 of shell 17.

The upper end of conduit 46 connects with passage 47 in the upper part of shell 16 which, in turn, connects with passage 48 in case 2 through the hollow bolt 49. The outer end of passage 48 is closed by the head of the bolt.

The nozzle 50 at the opposite end of passage 48 is located adjacent the chain 3 on the upper side of rail 6 to direct a stream of oil to the chain as the saw is operated.

4

The by-pass valve 51 in shell 17 opens into recess 43 and when open allows oil to pass from pump 37 back to the oil reservoir through passage 52 in shell 17. The valve 51 is of the plunger type and the plunger extends through the shell 17 and has an oil seal 53. The spring 54 on the outside of shell 17 encircles the plunger and bears outwardly against the plunger head to normally bias valve 51 in a direction to close the same. The adjustable screw 55 carried by thrust plate 26 engages the end of valve 51 so that when clutch 14 is disengaged by moving rod 25 within shaft 12, screw 55 also moves the plunger of valve 51 against the biasing action of spring 54 to open the valve and allow the oil to return to the reservoir through passage 52.

The oil filler plug 56 and vent screw 57 are conveniently located in the upper parts of chambers 22, respectively, of shell 17.

Varying amounts of oil may be delivered to the saw by adjustment of screw 55 providing for predetermined by-passing of the oil at all times.

The plunger pump is wholly disposed within the oil reservoir so that no leakage and loss of oil is possible and the entire oiling system is internally disposed within the transmission case 2 and shells 16 and 17.

The oil system and pump is fully operative in all operative positions of the saw, and always functions when the clutch is closed to drive the chain.

The invention provides a simple structure which is readily adapted for conversion of equipment to improve the oiling of the saw. The chain is oiled on the top of the guide rail just as the chain emerges from the drive mechanism, and the oil remains on the chain without being thrown off and is distributed thereon by the time it reaches the outer end of the guide rail so that the oil remains on the chain as it returns through the cut.

Various embodiments of the invention may be employed within the scope of the accompanying claims.

I claim:

1. A clutch and lubrication assembly for a chain saw comprising a driving sprocket for the chain, a shaft rotatably carrying said sprocket, a clutch carried by said shaft selectively connecting said shaft and sprocket for driving the latter, an oil pump operated by said shaft independently of the driving connection of said shaft and sprocket, an oil reservoir enclosing said pump, an oil passage within the body of said reservoir for delivery of oil from said reservoir to said pump, a second oil passage from said pump to the chain, a pressure relieving spring closed valve for said second passage and disposed to discharge into said reservoir, and a common actuator connected to said clutch and said relieving valve providing for selective closing of said valve by its spring when said clutch is engaged and opening said valve when said clutch is disengaged.

2. A transmission and lubrication assembly for a chain saw and the like comprising driver and driven gears, a transmission case for said gears, an oil reservoir closing and secured to said transmission case, a hollow shaft carrying said driven gear and carried by and extending through said case and reservoir, a clutch mounted on said shaft and disposed to drive the chain from the shaft, a clutch operating rod extending longitudinally through said shaft, an oil delivery system within said reservoir oper-

ated by said shaft, a pressure nozzle disposed to deliver oil from said system to the saw chain, valve means for controlling the operation of said system, and a common actuator for said valve means and said clutch operating rod to simultaneously selectively control the oil delivery of said system and the operative engagement of said clutch.

3. An assembly for an engine driven chain saw and the like comprising driving and driven gears, an oil delivery pump, a shaft carrying said driven gear and connected to said pump, a case carrying said shaft having a first chamber enclosing said gears and to contain lubricant therefor and a removable closure member therefor comprising a second chamber for oil and enclosing said pump, and oil passages disposed to deliver oil from said second chamber to said pump and from said pump to the saw chain.

4. A transmission and lubrication assembly for a chain saw and the like comprising a sprocket for the chain, a clutch for said sprocket, driving and driven gears, an oil delivery pump, a shaft carrying said clutch and said driven gear and operatively connected to said pump, a case carrying said shaft having a first chamber enclosing said gears and to contain lubricant therefor and a second chamber for oil and enclosing said pump, oil passages within the walls of said case delivering oil from said second chamber to said pump and from said pump to the chain, a by-pass opening from said last named passage within the wall of said case into said second chamber, a valve carried by said case controlling said by-pass, and mechanism carried by said case and connected to said clutch and said valve to operate the same in correlation.

5. In an engine driven chain saw, an engine, a chain carried by a guide rail, a driving sprocket for the chain disposed at one end of the rail, a clutch, a shaft carrying said clutch and the driving sprocket, transmission gears connecting the engine and said shaft, a case carrying said shaft for enclosing said gears and connecting the engine and said one end of the rail, an oil pump operatively connected to said shaft, an oil reservoir secured to said case and enclosing said pump, a passage from said reservoir and having an outlet adjacent the chain for delivering oil thereto, a pressure relieving valve for said pump opening into said oil reservoir, and mechanism connected to said clutch and said valve for selectively closing said valve when said clutch is engaged and opening said valve when said clutch is disengaged.

6. In an engine driven chain saw, an engine, a chain carried by a rail, a driving sprocket disposed at one end of the rail, a clutch, a shaft carrying said clutch and the driving sprocket, transmission gears connecting the engine and said shaft, a case carrying said shaft for enclosing said gears and connected to said one end of the rail, a bearing rotatably connecting said case and the engine providing selective angular adjustment of said case and the rail and chain relative to the engine, an oil pump operatively connected to said shaft, a shell secured to one end of said case providing an oil reservoir, an oil passage within the walls of said case having an outlet adjacent the chain, a pressure relieving valve for said pump discharging into said reservoir, said oil pump and passage and said shell being rotatable with said case, a control lever mounted on the engine, and means connecting said lever and said clutch and flexible

mechanical valve for selectively controlling the operation of said clutch and valve in correlation.

7. In a chain saw having a power source, an oil reservoir, and adjustable oil-pumping and delivery means driven directly by the power source, said means including a manual valve-controlled passage for return of oil to said reservoir and a delivery passage having a restricted orifice directed toward the saw chain whereby a predetermined volume of oil from said reservoir is applied to the chain immediately upon closing of said return passage for lubrication of the chain during the operation of the latter.

15 8. In a chain saw having a power source and a clutch operatively connecting the power source and the chain, a chain lubricant reservoir, pumping means driven by the power source, a supply passage from said reservoir to said pumping means, a delivery conduit from said pumping means terminating adjacent to the saw chain, a return conduit from said pumping means to said reservoir, valve means controlling at least one of said conduits, and a manually operable 20 lever connected to said clutch and said valve means for controlling the delivery of oil from said pumping means selectively to said reservoir and to the chain in correlation to the operation of the clutch, whereby a volume of lubricant 25 from said reservoir is immediately available for application to the chain during chain operation.

9. In a chain saw, an engine, a driven shaft having a sprocket at one end thereof adapted to drive the chain, a transmission case supporting 35 said one end of said driven shaft and having a chamber with an opposite opening, a guide rail for the chain rigidly secured to said transmission case, a passage within said case from adjacent the opening thereof and terminating adjacent to the chain, an oil delivery system 40 including a piston operatively mounted on said driven shaft, and a shell forming an oil reservoir and having a cylinder operatively supporting said piston, said shell being removably secured within said opening of said case to close the chamber thereof and including an oil delivery conduit from said cylinder having an open end disposed to register with said passage for the delivery of oil thereto and to the chain.

50 10. In a chain saw, an engine including a crankshaft and a crankcase therefor, a bevel drive gear secured to the end of said crankshaft exteriorly of said crankcase, a driven shaft having a sprocket at one end thereof adapted to 55 drive the chain and a bevel gear meshing with said first named gear, a transmission case supporting said one end of said driven shaft and having a chamber with an opposite opening, a guide rail for the chain rigidly secured to said transmission case, said case being rotatably secured to said engine crankcase for relative adjustment of said guide rail on the axis of said bevel drive gear, a passage within said case from adjacent the opening thereof and terminating adjacent to the chain, an oil delivery system 60 including a pump operatively mounted on said driven shaft, an oil reservoir enclosing said pump and removably secured within the opening of said case to close the chamber, said reservoir including an oil delivery conduit from said pump disposed to register with said passage for the delivery of oil to the chain and having a bearing supporting the other end of said driven shaft.

65 11. In a chain saw, an engine, a guide rail

carrying the saw chain, a transmission case carrying said guide rail and connected to said engine for relative rotation on an axis to dispose the guide rail in any of several cutting positions, a sprocket carried by said transmission case for driving the saw chain, transmission means driven by said engine and including a shaft carried by said transmission case, a clutch selectively connecting said shaft and sprocket and including means for control thereof by the operator, a chamber for a chain lubricant formed by said transmission case, fluid pressure means having a passage connected to said chamber to receive lubricant therefrom and a relief passage from said pressure means to said chamber for recirculation of the lubricant, said fluid pressure means being contained within said transmission case and driven by said shaft independently of the operative connection of the engine with said sprocket by said clutch whereby said pressure means is in operation at all times concurrently with the operation of the engine, a second passage from said pressure means having a restricted opening adjacent to the saw chain for delivery of the lubricant thereto, and valve means adapted to be controlled by the operator and to close said return passage whereby the lubricant is immediately directed through said second passage to the saw chain.

12. In a chain saw, an engine, a guide rail carrying the saw chain, a sprocket driving the saw chain, transmission means driven by said engine and including a shaft, a clutch selectively

10
5
15

connecting said shaft and sprocket including means for control thereof by the operator, a reservoir for a chain lubricant, fluid pressure means having a passage connected to said reservoir to receive lubricant therefrom and a relief passage from said pressure means to said reservoir for recirculation of the lubricant, said fluid pressure means being driven by said shaft independently of the operative connection of the engine with said sprocket by said clutch whereby said pressure means is in operation at all times concurrently with the operation of the engine, a second passage from said pressure means and having a restricted opening adjacent to the saw chain for delivery of the lubricant thereto, and valve means adapted to be controlled by the operator and to close said return passage whereby the lubricant is immediately directed to said second passage and the saw chain.

ELMER C. KIEKHAEFER.
